UNITED STATES PATENT OFFICE.

ARTHUR H. SYMONS, OF CHICAGO, ILLINOIS, ASSIGNOR TO SYMONS CLAMP & MFG. COMPANY, OF CHICAGO, ILLINOIS, A CORPORATION OF ILLINOIS.

COLUMN CLAMP.

Application filed January 11, 1928. Serial No. 245,838.

The invention relates to clamps for holding together the separable sections or frames that form a mold into which concrete or other plastic material is poured and set in the construction of buildings and other concrete structures, and more particularly to those clamps which comprise sets of pivotally connected bars, the ends of which are arranged to intersect each other, and blocks or brackets adapted to connect the intersecting ends of the bars and cooperate with wedges to clamp or draw the sets against the sides of the sections so as to hold the latter in connected relation during the pouring and setting periods.

The primary object of the present invention is to provide a clamping unit of this character in which the blocks or brackets are of new and improved construction and are reinforced so as to withstand in an efficient manner the comparatively great forces and thrust to which they are subjected.

Another object of the invention is to provide a bracket for a mold or form clamping unit which may be quickly applied to the intersecting bars and embodies means for effectively holding the latter in rigid relation.

A further object of the invention is to provide a bracket having a stop lug which is so arranged that when the bars are in their inoperative or overlapped position, the bar which is not connected to the bracket is prevented from being swung in the wrong direction with respect to the bracket of the other unit. As a result, when the clamp is to be used, the free bar must be swung in the proper direction to fit within the bracket of the other unit.

A still further object of the invention is to provide a form or column clamp which may be easily and economically manufactured, is efficient in operation and may be readily adjusted into its operative position.

Other objects will appear hereafter from the detailed description.

The invention consists in the several novel features hereinafter set forth and more particularly defined by the claims at the conclusion hereof.

In the drawings which form a part of this description or specification and in which like numerals of reference denote corresponding parts throughout the several views:

Figure 1 is a transverse sectional view of a

mold to which is applied a clamp embodying the invention.

Figure 2 is a perspective view of one end of the clamp, showing the manner in which the intersecting bars are held in one of the new and improved brackets.

Figure 3 is a perspective view of the bracket shown in Figure 2.

Figure 4 is a perspective of the bracket viewed from the bottom.

Figure 5 is a section taken on line 5—5 of Figure 2.

Figure 6 is a section taken on line 6—6 of Figure 2.

Figure 7 is a plan view of a pair of units, illustrating the manner in which they are assembled for use and how the stop lugs operate to cause the free bars to be swung only in the proper direction with respect to the brackets.

Figure 8 is an enlarged section taken on line 8—8 of Figure 7.

The invention is exemplified in a clamp for securing together in squared relation the four sides or sections of a mold for forming a column of concrete, cement, or any other plastic material. The sections are separable and together form a rectangular mold in which the concrete is poured and allowed to set, as well understood in the art. The clamp which forms the subject matter of the present invention comprises a pair of units, each consisting of two bars 10 which overlap each other at one end and are there pivotally secured together by a rivet or bolt 11. The bars are made of any desired length and are preferably formed of strap iron, the distal ends thereof being each provided with a longitudinal series of transverse openings or slots 12 for receiving a wedge 13. In applying the units to the mold, the bars 10 are positioned against the sections respectively and are arranged so that the pivoted ends are at two diagonally opposite corners and the distal or slotted ends intersect each other at the other corners. The intersecting ends of the bars are connected together by a pair of blocks or brackets 14, which cooperate with the wedges 13 to urge the bars into clamping relation.

Each unit or pair of bars is provided with one bracket 14. The latter is formed of a one-piece casting and comprises a pair of rigidly connected arms 15 and 16 which extend at right angles to each other and are adapted to receive the intersecting ends of

the bars. The arm 15 comprises an upper wall 17 and a lower wall 18 which are spaced apart by a side wall 19 to form an elongated chamber 20 in which the end of one of the 5 bars 10 fits and is longitudinally slidable. The upper wall 17 has formed therein a pair of longitudinally extending slots 21 which are aligned with a pair of slots 22 formed in the lower wall 18 and form therewith sockets for one of the wedges 13. The slots 21 and 22 are spaced apart respectively distances which are different than the spaces between the slots 12 with the result that there is always one combination of slots (21, 12 and 15 22) through which the operator may insert a wedge 13 and upon driving the wedge down, secure relative movement of the bar and arm for clamping purposes. The outer faces of the walls 17 and 18 are provided 20 adjacent the wedge slots with a pad or reinforced portion 23 which operates to strengthen the parts that contact with the wedge. The inner end of the lower wall projects beyond the upper wall 17 and is mitered, as at 24, to form a triangular bearing surface 25. The arm 15 preferably holds the lowermost bar and this surface together with the remainder of the lower wall 18 forms a comparatively large bearing upon which the 25 bar rests and is slidable. The side wall 19 is disposed at the so-called outer part of the bracket and forms an abutment for the outer edge of said lowermost bar, i. e. the bar which extends through the chamber 20. The 30 fourth side of the latter is closed by a side wall 26 which is formed integrally with the inner side margins of the walls 17 and 18. This side wall is positioned with respect to the side wall 19 so that the bar is confined 35 against transverse angular movement while in the chamber 20. To prevent the arm 15 from sliding off the free end of the bar when free to slide thereon a stop lug 27 is provided. This lug is connected to said bar adjacent the slotted end and inner edge thereof and serves to retain the bracket 14 in connected relation with the unit or pair of bars with which it is associated. To permit the 40 arm 15 to be shifted to the extreme distal end of the bar before being arrested by the stop lug, the upper and lower walls of the arm 15 and the side wall 26 are cut away as at 28. The lowermost part of the side wall 26 and the mitered margin of the surface 24 project downwardly beyond the outer face of the lower wall 18 to form a reinforcing rib or bead 29 which operates to strengthen said lower wall. The uppermost part of the side wall 26 and the margin at the inner end 45 of the upper wall 17 extend upwardly beyond the outer face of the upper wall and the pad 23 to form a reinforcing rib 30.

The arm 16 of each bracket comprises an upper wall 31 and a lower wall 32 which are spaced apart by an integral side wall 33 to

form an elongated chamber 34 in which the uppermost bar fits and is longitudinally slidable. The inner face of the lower wall 32 is coplanar with respect to the inner or lower face of the wall 17 so that the chamber 70 34 is positioned directly above the level of the chamber 20 with the result that the intersecting portions of the bars rest one upon the other as shown in Figures 2 and 6. The front or inner end 35 of the lower wall 32 75 forms a continuation of the side wall 19 and assists the latter in forming an abutment for the outer edge of the lowermost bar 10. The front end 35 is connected to the subjacent margin of the mitered portion of the lower 80 wall 18. The inner face of the side wall 33 is coplanar with the inner end of the wall 17 and forms therewith an abutment for the outer edge of the uppermost bar 10. The inner side of the arm 16 is left open so that 85 said uppermost bar 10 may be inserted edge-wise or laterally into the chamber 34 to facilitate assembly of the clamping unit. Similarly to the walls 17 and 18, the upper and lower walls 31 and 32 have formed therein 90 wedge slots 36 and 37. These slots are spaced apart the same distance as the slots 21 and 22 so that always one combination of slots (36, 12 and 37) is available for the insertion of a wedge 13. Reinforcing portions or pads 95 38 are formed on the outer faces of the walls 31 and 32 adjacent the wedge slots. The inner margin 39 of the lower wall 32 extends downwardly to form a continuation of the rib 29. The inner or front end and the 100 inner side margin of the upper wall 31 extend upwardly to form a continuation of the rib 30.

In actual practice the bars 10, due to the outward pressure of the mold sections, exert 105 considerable force upon the brackets 14. To strengthen these brackets so that the arms 15 and 16 will be rigid and capable of withstanding great cross forces, a triangular shaped web 40 is arranged between said arms. This 110 web is formed integrally with the outer side margins of the upper wall 17 and the lower wall 32 and extends therebetween. To prevent the upper and lower walls of the arms 16 and 17 from being forced apart or broken due 115 to rocking movement of the bars 10, U-shaped members 41 are provided. These members are formed as an integral part of the bracket and extend around the upper, lower and inner side walls of each arm, as illustrated in 120 Figures 3 and 4. The connecting part 42 of each member is thickened while the legs 43 taper outwardly with the result that the members strengthen the arms 15 and 16 in a most efficient manner.

The clamp is operated as follows: The two units or pairs of bars 10 are applied to the mold sections with the pivot pins 11 at diagonally opposite corners. The distal ends of the bars are then overlapped as illustrated 125 130

in Figure 1 and the uppermost bars are shifted outwardly into the open-ended chambers 34 in the brackets 14 so as to interlock and connect together the units. The intersecting portions of the bars are then forced apart manually as far as possible to jam the sets into close contact with the sections of the mold, while at the same time the brackets 14 are shifted in a follow up manner. Thereafter the wedges 13 are inserted into the wedge slots and driven down as far as possible to urge the inner edges of the bars which extend between the overlapped ends and the pivoted connections into their clamping position against the mold sections. In this manner the mold is held together while the plastic material is poured therein and allowed to set. When it is desired to remove the clamping unit slight tapping on the small ends of the wedges operates to release the latter so that they may be withdrawn and the unit dismantled.

When the units are not in use the uppermost bar 10 is swung toward the bracket 14 and forced on top of the arm 16 so that the two bars 10 are in overlapped relation (see Figures 7 and 8). In this position the arms take up but little space and the bracket 14 is held so that it cannot slide back and forth on the lowermost bar 10 which is very desirable in shipping and transporting. When the units are to be used, the uppermost bar is swung so as to extend at right angles to the lowermost bar and to fit edgewise within the open-ended chamber 34 in the bracket of the cooperating unit. To prevent the uppermost bars 10 from being swung in the wrong direction, a stop lug 44 is formed on the top of each of the brackets. This lug is formed as an integral part of the bracket and comprises an abutment member 45 which projects upwardly from the upper wall 31 and extends parallel with respect to the arm 15. When the uppermost bar is shifted into its inoperative position it abuts against this wall (Figure 8) and is limited thereby to movement only in the proper direction for use with the bracket of the cooperating unit. The abutment member 45 is of such a height that the uppermost bar 10 cannot be conveniently forced thereover. The lug 44 also comprises a reinforcing wall 46 which extends at right angles to the abutment member. The rib 30 serves to support and direct the uppermost bar into its inoperative position. Because the legs 43 of the U-shaped members 41 are tapered they do not interfere in any manner with the bar shifting operation just described.

The clamp herein disclosed operates effectively to hold together the separable sections of a column mold, includes a bracket for holding the intersecting bar ends which is of new and improved construction and may be manufactured at a comparatively low cost.

Additionally, the bracket of the clamp may be readily adjusted into its operative position and is reinforced at the points and places subjected to the most strain.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a clamp of the character described, the combination of a pair of bars, the ends of which overlap and are each provided with a longitudinal series of slots, a one-piece bracket for holding the ends of the bars in their overlapped position comprising a pair of arms adapted to be associated with the bars respectively and extend outwardly from the overlapping parts toward the extremities of said ends of the bars, one of the arms having an elongated chamber formed therein in which the lowermost bar fits and is longitudinally slidable only, the other arm being provided with an elongated open-sided chamber in which the uppermost bar fits edgewise and is longitudinally slidable, said arms being provided with slots, and wedges extending through the slots in the arms and bars for holding the bracket and bars in their operative position.

2. In a clamp of the character described, the combination of a pair of bars, the ends of which overlap and are each provided with a longitudinal series of slots, a one-piece bracket for holding the ends of the bars in their overlapped position comprising a pair of arms adapted to be associated with the bars respectively and extend outwardly from the overlapping parts toward the extremities of said ends of the bars, one of the arms having an elongated chamber formed therein in which the lowermost bar fits and is longitudinally slidable, the other arm extending outwardly from the outer edge of said lowermost bar and being provided with an elongated open-sided chamber in which the uppermost bar fits edgewise and is longitudinally slidable, said arms being provided with slots and being reinforced and held in rigid relation by an integral substantially triangular web positioned between the outer side portions of said arms, and wedges extending through the slots in the arms and bars for holding the bracket and bars in their operative position.

3. In a clamp of the character described, the combination of a pair of bars, the ends of which are adapted to intersect each other and are provided with slots, a one-piece bracket for holding said bars in their operative position consisting of a pair of arms, each of said arms consisting of an upper and a lower wall, one of the arms having a pair of side walls which form with its upper and lower

walls an elongated chamber in which one of the bars fits and is longitudinally slid able only, the other arm having but a single side wall which forms with its upper and lower 5 walls, an elongated open-sided chamber in which the uppermost bar fits edgewise and is longitudinally slid able, the upper and lower walls of the arms being provided with slots, and wedges extending through the slots 10 in the walls and bars for holding the bracket and bars in their operative position.

4. In a clamp of the character described, the combination of a pair of bars, the ends of which overlap each other and are provided 15 with slots, a one-piece bracket for holding said bars in their overlapped position comprising of a pair of arms extending at right angles to each other, each of said arms consisting of an upper and a lower wall, one of 20 the arms having a pair of side walls which form with its upper and lower walls an elongated chamber in which the lowermost bar fits and is longitudinally slid able, the other arm having but a single side wall which 25 forms with its upper and lower walls an elongated open-sided chamber in which the uppermost bar fits edgewise and is longitudinally slid able, the upper and lower walls of the arms being provided with slots, and wedges 30 extending through the slots in the walls and bars for holding the bracket and bars in their operative position.

5. In a clamp of the character described, the combination of a pair of bars, the outer 40 ends of which overlap each other and are provided with slots, a one-piece bracket for holding said bars in their overlapped position comprising a pair of arms extending at right angles to each other, each of said arms consisting of an upper and a lower wall, one 45 of the arms having a pair of side walls which form with its upper and lower walls an elongated chamber in which the lowermost bar fits and is longitudinally slid able, the other arm having a side wall which forms with its upper and lower 50 walls an elongated chamber in which the uppermost bar fits and is longitudinally slid able, the inner end of the lower wall of said other arm being coplanar with the outer side 55 wall of the said one arm and forming a continuation of the side wall of said other arm, the upper and lower walls of the arms being provided with slots, and wedges 60 extending through the slots in the walls and bars for holding the bracket and bars in their operative position.

6. In a clamp of the character described, the combination of a pair of bars, the ends of which overlap each other and are provided 65 with slots, a one-piece bracket for holding said bars in their overlapped position con-

sisting of a pair of arms extending at right 65 angles to each other, each of said arms consisting of an upper and a lower wall, one of the arms having a pair of side walls which form with its upper and lower walls an elongated chamber in which the lowermost bar 70 fits and is longitudinally slid able, the other arm having but a single side wall which forms with its upper and lower walls an elongated open-sided chamber in which the uppermost bar fits edgewise and is longitudinally 75 slid able, the inner end of the upper wall of said one arm being coplanar with and forming a continuation of said single side wall, the upper and lower walls of the arms being provided with slots, and wedges 80 extending through the slots in the walls and bars for holding the bracket and bars in their operative position.

7. In a clamp of the character described, the combination of a pair of bars, the ends 85 of which overlap each other and are provided with slots, a one-piece bracket for holding said bars in their overlapped position comprising 90 a pair of arms extending at right angles to each other, each of said arms consisting of an upper and a lower wall, one of the arms having a pair of side walls which form with its upper and lower walls an elongated chamber in which the lowermost bar fits and is longitudinally 95 slid able, the other arm having a side wall which forms with its upper and lower walls an elongated chamber in which the uppermost bar fits and is longitudinally slid able, the inner end of the lower wall of said other arm being coplanar with the outer side 100 wall of the said one arm and forming a continuation thereof against which the lowermost bar abuts, the upper and lower walls of the arms being provided with slots, and wedges 105 extending through the slots in the walls and bars for holding the bracket and bars in their operative position.

8. In a clamp of the character described, the combination of a pair of bars, the outer 110 ends of which overlap each other and are provided with slots, a one-piece bracket for holding said bars in their overlapped position comprising a pair of arms extending at right angles to each other, each of said arms consisting of an upper and a lower wall, one of the 115 arms having a pair of side walls which form with its upper and lower walls an elongated chamber in which the lowermost bar fits and is longitudinally slid able, the other arm having but a single side wall which forms with its upper and lower walls an elongated open-sided chamber in which the uppermost bar fits edgewise and is longitudinally slid able, the inner end of the lower wall of said other arm being coplanar with the outer side wall 120 of the said one arm and forming a continuation thereof against which the lowermost bar abuts, the upper and lower walls of the arms 125

being provided with slots, and wedges extending through the slots in the walls and bars for holding the bracket and bars in their operative position.

5. In a clamp of the character described, the combination of a pair of bars, the outer ends of which overlap each other and are provided with slots, a one-piece bracket for holding said bars in their overlapped position 10 comprising a pair of arms adapted to be associated with the bars respectively and extend outwardly from the overlapping parts toward the extremities of said ends of the bars, each of said arms consisting of an upper and 15 a lower wall, one of the arms having a pair of side walls which form with its upper and lower walls an elongated chamber in which the lowermost bar fits and is longitudinally slid able, the other arm having a side wall 20 which forms with its upper and lower walls an elongated chamber in which the uppermost bar fits and is longitudinally slid able, the inner end of the lower wall of said one arm being extended to form a comparatively long 25 bearing surface for said lowermost bar, the upper and lower walls of the arms being provided with slots, and wedges extending through the slots in the walls and bars for holding the bracket and bars in their operative 30 position.

10. In a clamp of the character described, the combination of a pair of bars, the outer ends of which overlap each other and are provided with slots, a one-piece bracket for holding said bars in their overlapped position 35 comprising a pair of arms adapted to be associated with the bars respectively and extend outwardly from the overlapping parts toward the extremities of said ends of the bars, 40 each of said arms consisting of an upper and a lower wall, one of the arms having a pair of side walls which form with its upper and lower walls an elongated chamber in which the lowermost bar fits and is longitudinally 45 slid able, the other arm having but a single side wall which forms with its upper and lower walls an elongated open-sided chamber in which the uppermost bar fits edgewise and is longitudinally slid able, the inner end of the 50 lower wall of said one arm being extended and connected to the inner end of the lower wall of said other arm to form a relatively long bearing surface for said lowermost bar, the upper and lower walls of the arms being provided with slots, and wedges extending through the slots in the walls and bars for holding the bracket and bars in their operative 55 position.

11. In a clamp of the character described, 60 the combination of a pair of bars, the ends of which overlap each other and are provided with slots, a one-piece bracket for holding said bars in their overlapped position comprising a pair of arms extending at right 65 angles to each other, each of said arms

consisting of upper and lower walls and side walls forming an elongated longitudinal chamber in which one of the bars fits and is slid able, the arms being arranged so that the chambers are disposed at 70 different levels, the bracket also comprising a substantially triangular web positioned co-planar and formed integrally with the upper wall of one arm and the lower wall of the other arm and extending therebetween, the 75 upper and lower walls of the arms being provided with slots, and wedges extending through the slots in the walls and bars for holding the bracket and bars in their operative 80 position.

12. A unit for a column clamp, comprising a pair of bars pivotally connected together at one end thereof and having wedge openings in their other ends, and a bracket slidably mounted on the lowermost bar and provided with a chamber for receiving and retaining the uppermost bar of another unit, the uppermost bar of the instant unit being adapted to be shifted over the bracket and into an inoperative and overlapped position 90 with respect to the said lowermost bar, and means on the bracket for limiting pivotal movement of said second mentioned uppermost bar to one direction when the bar is in its inoperative position. 95

13. A unit for a column clamp, comprising a pair of bars pivotally connected together at one end thereof and having wedge openings in their other ends, and a bracket slidably mounted on the lowermost bar and provided with a chamber for receiving and retaining the uppermost bar of another unit, the uppermost bar of the instant unit being adapted to be shifted over the bracket and into an inoperative and overlapped position 100 with respect to the said lowermost bar, and a stop lug formed integrally with the bracket for limiting pivotal movement of said second mentioned uppermost bar to one direction when the bar is in its inoperative position. 105

14. A unit for a column clamp, comprising a pair of bars pivotally connected together at one end thereof and having wedge openings in their other ends, a bracket slidably mounted on the lowermost bar, said bracket being provided with a transversely extending rib above said lowermost bar and having formed therein a chamber for receiving and retaining the uppermost bar of another unit, the uppermost bar of the instant unit being adapted to be shifted over the bracket and upon the rib in its inoperative position, and a stop lug connected to the bracket adjacent one end of the rib for limiting pivotal movement of said second mentioned uppermost bar to one direction when the bar is in its inoperative position. 115

15. In a clamp of the character described, the combination of a pair of bars, the ends 120

of which intersect each other and are provided with slots, a one-piece bracket for holding said bars in their operative position comprising a pair of arms extending at right angles to each other, each of said arms consisting of an upper and a lower wall, one of the arms having a pair of side walls which form with its upper and lower walls an elongated chamber in which the lowermost bar fits and is longitudinally slid able, the other arm having a side wall which forms with its upper and lower walls an elongated chamber

in which the uppermost bar fits and is longitudinally slid able, the upper and lower walls of the arms being provided with slots, wedges 15 extending through the slots in the walls and bars for holding the bracket and bars in their operative position, and U-shaped reinforcing members connected to the arms and extending around the upper and lower and outer side 20 walls.

Signed at Chicago, Illinois, this 14th day of December, 1927.

ARTHUR H. SYMONS.
